(57) **CLAIM**

The ornamental design for a Jewish Religious Ornament, as shown and described.

DESCRIPTION

FIG. 1 is a front view of one of the four identical components of the Jewish Religious Ornament, shown separate from the assembled ornament for clarity and completeness of disclosure;

FIG. 2 is a side view of FIG. 1;

FIG. 3 is a perspective view of the assembled Jewish Religious Ornament embodying my new design;

FIG. 4 is another perspective view of the design shown in FIG. 3;

FIG. 5 is a front view of FIGS. 3 and 4;

FIG. 6 is a top view of FIGS. 3-5, the bottom view being identical to the top; and,

FIG. 7 is a side view of FIGS. 3-6.
